UNITED STATES PATENT OFFICE.

JAMES PHILLIPS, JR., OF FITCHBURG, MASSACHUSETTS, ASSIGNOR TO THE
FITCHBURG WORSTED COMPANY, OF SAME PLACE.

DESIGN FOR FABRIC.

UNITED STATES PATENT OFFICE.

JAMES PHILLIPS, JR., OF FITCHBURG, MASSACHUSETTS, ASSIGNOR TO THE FITCHBURG WORSTED COMPANY, OF SAME PLACE.

DESIGN FOR FABRIC.

SPECIFICATION forming part of Design No. 16,919, dated September 28, 1886.

Application filed August 7, 1886. Serial No. 210,370. Term of patent 3½ years.

To all whom it may concern:

Be it known that I, JAMES PHILLIPS, JR., of Fitchburg, in the county of Worcester and State of Massachusetts, have invented a new and original Design for Fabric, of which the following is a full, clear, and exact description.

Reference is to be had to the accompanying photograph of my newly-designed fabric.

The leading feature of my design consists of stripes of considerable width of uniform color separated by narrower stripes made up of triangular figures of different colors.

A represents the stripes of uniform color, and B the narrower stripes interposed between the stripes A. The stripes A are of corkscrew design, showing small diagonal ribs or spirals *a a*, while the stripes B show figures *b c* of different colors. These figures of different colors are triangular in shape, and small diagonal stripes *d* appear between them, and a rib

or small border, *e*, appears at each side of the narrow stripes B.

I claim—

1. The design for fabric herein shown and described, the same consisting of the stripes A, showing diagonal ribs *a*, the interposed narrow stripes B, showing figures of different colors, and a rib or border, *e*, at each side of the stripes B. 25

2. The design for fabric herein shown and described, the same consisting of the stripes A, of solid color, and the interposed stripes B, showing triangular figures *b c* of different colors, and small diagonal stripes *d* between the figures *b c*. 30

JAMES PHILLIPS, JR.
